UNITED STATES PATENT OFFICE.

PETER G. TEN EYCK, OF ALBANY, NEW YORK.

RAILWAY SIGNAL AND SWITCH OPERATING MEANS.

1,111,930.

Specification of Letters Patent. Patented Sept. 29, 1914.

Application filed August 24, 1909. Serial No. 514,413.

To all whom it may concern:

Be it known that I, PETER G. TEN EYCK, a citizen of the United States, and a resident of Albany, county of Albany, and State of New York, have invented certain new and useful Improvements in Railway Signal and Switch Operating Means; and I do hereby declare the following to be a full, clear, and exact description of the same, reference being had to the accompanying drawings, forming a part of this specification, and to the figures and letters of reference marked thereon.

This invention relates to railway switch and signal operating systems and more especially to systems wherein a series of stations, such as switches or signals, or both, are operated or controlled from a tower or central station.

The primary object of the invention is to reduce the number of line connections extending from the stations to the tower without in any wise limiting the capacity of the system either with respect to the control and operation of the switches or signals or with respect to the indicating mechanism in those systems where return indications are desired.

Further objects of the invention are to reduce the cost of operation and increase the efficiency both with respect to the operation of the instrumentalities employed and with respect to safety in guarding against false movements and indications.

The invention consists primarily in a system embodying a tower or operating station, a series or plurality of switch or signal stations distant from the tower and operating line connections including an individual line for each switch or signal station and two return lines both common to all the switch or signal stations, whereby succeeding stations require but one line to the tower and the extension of the two common lines from the next adjacent switch or signal station in the series.

The invention further consists in the employment of separate and independent sources of energy one in association with each of the returns common to all the switch or signal stations and instrumentalities whereby either may be associated with an individual line to each switch or signal sta-

tion to complete an operating circuit to throw the switch or signal in one direction or the other.

The invention further consists in certain novel details of construction and combinations and arrangements of parts, all as will be hereinafter described and pointed out particularly in the appended claims.

The invention is primarily, though not exclusively, designed for embodiment in an electrical equipment, although, as will be readily understood by those skilled in the art, it may be embodied in systems employing motive fluid as the controlling or the operating means, but for the purposes of illustration a system having electrical equipment throughout has been adopted.

In the accompanying drawings Figure 1 is a diagrammatic illustration of a system embodying the present invention, three switch stations being shown, one of said stations being an extension of another and controlled thereby. Fig. 2 is a similar view of a system embodying the invention and in which the sources of operating energy are utilized as the sources of energy for indicating. Figs. 3, 4, 4^a, 5 and 5^a are diagrammatic elevations on an enlarged scale of one of the operating levers shown on a reduced scale in Fig. 1, the different figures showing the lever in other positions of adjustment than that shown in Fig. 1; Fig. 6 is an enlarged diagrammatic detail of the circuit arrangement of one of the switch motors, this arrangement corresponding to the arrangement shown in Fig. 1; Fig. 7 is a view corresponding to Fig. 6, but showing the arrangement of the switch motors employed in Fig. 2.

In said drawings, the tower or control station is indicated at A, the signal or switch stations at B and C, respectively, and the extension signal or switch station at C'. For the purpose of illustrating the invention as applied in switch operating and indicating systems, railway tracks D are shown in Fig. 1 with a switch b at station B and cross-over switches c and c' at stations C and C', respectively.

Each switch or signal station is equipped with a switch or signal operating motor E which is adapted to move the switch or signal into successive positions coming to rest

between each movement, for instance, the motor when energized through one set of connections will move the switch to one position and when energized through another set of connections will move the switch to another position and the switch is thus opened or closed, as the case may be. Apparatus of this character is well known and specific illustration or description is, therefore, unnecessary.

At the tower or control station A the usual inter-locking or operating levers or parts movable therewith are indicated at F—F', one such lever being usually provided for the control of each independent switch.

Each independent station has an individual line extending to the tower, said lines being shown in Fig. 1 at B² and C² for the respective stations. In addition, two separate and independent return lines G—G', common to all the stations are provided. When return indications are desired with the arrangement shown in Fig. 1 two additional independent returns H and H' common to all the stations are provided but for the present these indicator returns may be disregarded.

Each of the individual station lines B², C² is provided with contacts b², c², with which contacts b³, b⁴ and c³, c⁴ on the levers F—F' are adapted to engage when the levers are moved in one direction or the other. Contacts b³, c³ are electrically connected by wire g and with one side of a generator indicated by the battery G², the opposite side of said generator being connected with common return G. Contacts b⁴, c⁴ are likewise connected by a wire g' and to one side of a generator indicated by the battery G³, the opposite side of said generator being connected with common return G'.

The motor at each station is adapted to switch its own connections, *i. e.*, when operated to move a switch or signal in one direction and during its movement it shifts the motor contacts to a position for effecting the opposite movement of the switch when next energized. The contact switch moved by the motor is indicated at I in the drawings (Figs. 1 and 6) and it carries contacts i, i' adapted to connect one or the other of the common returns with the motor through branch wires i², i³.

As shown in Fig. 1, the switches are in normal position and the motor is connected through i with return G but no current flows because the circuit is broken at b³ or c³. If, however, one of the levers F or F' be moved from the full line position 2 to the dotted line position 3, its contact b⁴ or c⁴ will move away from b² or c² and contact b³ or c³ will engage therewith, thereby energizing the motor at the desired station from generator G² to operate the switch or signal to reverse

position. The movement of the motor breaks the return circuit G at i and establishes the return circuit G' at i' but this circuit having been broken at the lever no current flows and the motor comes to rest with the switch or signal in reverse position. A movement of the lever back to position No. 2 energizes the motor from generator G³ through return G' to restore the switch to normal and both operations are performed at any desired switch or signal station through a single individual station line and two returns common to all stations. Positions 2 and 3 of the levers F—F' are all that are necessary to operate the switch or signal motors but the levers have to assume positions 1 and 4 to release the mechanical interlocking as will presently appear. Positions 2 and 3 are the indicating positions or the positions in which the levers are automatically stopped or held until the switch or signal is moved to its new position and in so doing makes up the indicating contacts at the switch or signal and effects the release of the levers through the operation of magnets P, all as will be hereinafter explained.

The broad invention presents possibilities of combination with extension station equipments and with simple safety and lock devices and with switch and signal indicating means which become of great importance in a practical commercial installation and form an integral part of the system. For instance, a cross or short circuit which might give a false operation is effectually taken care of by providing magnets K, K' included in branch circuits from the common returns G and G' and terminating in contacts k, k'; respectively, adapted to be moved by the levers F, F' to engage contacts k² on the individual station lines. Said magnets K, K' control switches K² in the main operating circuits and in the event of a cross or short circuit the current will seek the path of least resistance and by energizing said magnets break the main energizing circuit, thereby preventing the accidental operation of the switch or signal motors. For example, a cross or shunt circuit between the reverse battery wire g and the operating wire B² with the lever F' normal, would result in a current to the switch motor E, whereby said switch motor would be reversed, but with the arrangement illustrated in the drawings, the cross or shunt circuit would cause current to flow primarily from the wire B² through contacts k², k and through the safety magnet K back to the reverse battery G². This current would instantly energize the safety magnet, and open the circuit at K², thereby preventing the operation of the switch motor by deenergizing the circuit established by the cross or accidental short-circuiting.

The safety magnet K may be a low resistance magnet and operates to break the circuit intermittently and so prevent the switch motor from starting against the resistance of the switch mechanism or it may be of one of the well known types which hold the circuit open until it is closed manually.

The switch motor when operated changes 10 the connections at the switch station to cut out one generator or battery and close the connections for the other battery to operate the motor for reversing the switch and the safety magnet is in position to prevent a 15 premature reverse operation of the motor should a cross or short circuit occur between the station wire B² and the wiring between the battery and the lever contacts. Any cross or short circuit between the station 20 wire B² and the common return would of itself short-circuit the switch motor and the latter would not operate.

A lock or safety magnet M may be also included in the main energizing circuit for 25 each station, and through the usual and well known appliances used in connection therewith prevent the premature operation of the levers. This safety magnet M is in series with the motor and is energized by the 30 motor operating current to lock the lever when current is on the motor, thereby holding the lever in indicating position (as will presently appear) until the motor has stopped operating. The safety magnet M 35 is operated by either motor operating generator and in practice is therefore operated alternately by generators G² and G³.

When it is desired to provide an extension station from any switch or signal station 40 without additional wiring to the tower this may be accomplished by providing branch lines from the primary station to the extension station controlled by the motor operated switch I at the primary station and 45 utilizing the two returns common to all stations.

The extension arrangement will be readily understood by reference to stations C and C', the latter being an extension station. At 50 station C the motor operated switch I carries contacts I' I² adapted to alternately make or break branch circuits N, N' leading to the station C'. At station C' circuits N, N' are adapted to be alternately made or 55 broken by contact n, n' on a switch I⁵ which latter corresponds to the switches I before described. The circuit N or N' established by the switch I⁵ extends to the operating motor E at station C' and through said 60 motor to one or the other of the common returns G, G' depending upon which branch has been closed by the movement of the switch I and tower lever. With the switches or signals in normal position, as shown in 65 the drawings, when the motor at C is oper-

ated to reverse the switch the branch N' will be closed by contact I² and as this branch is established at C' by contact n' the motor at C' will be energized to reverse the switch or signal at C' and to establish branch N at n for the return movement to normal position.

Commercial installations usually require that indicating means shall be provided for the information of the tower man as to whether or not the switch or signal has actually moved to the desired position and while the generators or sources of operating power may be utilized in the indicating system in connection with the two returns common to all stations, as will be presently explained, the arrangement shown in Fig. 1

70 wherein the individual line to each station and separate indicator returns common to all stations are employed, will be first described. Each tower lever F, F', etc., is provided with indicator circuit contacts O,

O' adapted to coöperate with terminal contacts o, o', the arrangement being such that when the lever is moved upwardly or away from the operator to position No. 2, which is normal indicating position, contacts O, o engage to establish the indicating circuit. A lever movement to position No. 1 (normal or home position) causes contacts O, o to 90 pass each other and they do not operatively engage when the lever is moved reversely because their rear faces are insulated as at o². Movement of the lever from position No. 1 to position No. 3 (reverse indicating position) brings contacts O', o' into operative engagement and movement to position No. 4 (reverse position) breaks the indicating circuit at O', o', all as will be readily understood.

The movement of any lever from position No. 3 to position No. 4, or from position No. 2 to position No. 1 does two things;—first, it breaks the indicating circuit by causing contacts O, o or O', o' to move past each other and, secondly, it releases the usual mechanical interlocking mechanism and locks up all other diverging routes, as the case may require.

105 In the arrangement shown in Fig. 1, the contacts o, o' are in multiple in a branch of the individual station line (C² or B²) said branch including an indicator magnet P. Besides the usual indicator this magnet controls a lock lever P' the lock arms p, p' of 110 which coöperate with projections p², p³ on the lever and prevent lever movement in the wrong direction; for instance, as shown, the magnet being energized the lever can move forward from normal indicating position up to normal or home position, and if the switch had not moved to normal position the magnet could not be energized and this movement would be prevented by the lock arm p engaging the bottom projection p². The movement of the lever to position No. 130

1 breaks the indicating circuit at O ; o , de-energizing P allowing lever P' to fall, releasing p' from p^3 . Should a short circuit occur or foreign current be on the indicating circuit the magnet P would be energized and p' engaging below p^3 would prevent the lever from being moved to reverse position. When the lever is in position No. 4, p' would under similar circumstances engage above p^3 and prevent operation of the lever. The magnet P must be energized to release p' from projections p^2 and deenergized to release p' from p^3 . By the provision of this locking means a cross or vagrant current is not permitted to allow the lever to move without waiting for the switch or signal to operate and indicate, nor can the mechanical interlock of the opposing routes be operated or released before the switch or signal has assumed its proper position, because the switch or signal makes up the contacts for energizing magnet P to operate latch P' , and release p^2 only when the switch or signal assumes its new position. The act of moving lever F or F' from 2 to 1 or from 26 3 to 4 releases the mechanical interlocking which latter may be of the well known kind commonly employed in both electric and mechanical interlocking machines for many years and which therefore forms no part of the present invention.

The control and operation of the levers F' will be better understood by reference to Figs. 3 to 5^a. In Fig. 3 the lever is shown in the normal home or No. 1 position. In Figs. 4 and 4^a it is shown in the No. 3 or reverse indicating position, and in Figs. 5 and 5^a it is shown in the No. 4 or reverse position. None of these positions are shown in Fig. 1 of the drawings, but are indicated by the dotted positions and numbers.

When the lever F' is in the No. 1 position, Fig. 3, the locking end or arm p rests on the bottom surface of the first lug p^2 . The magnet P is deenergized and its armature P' retracted, leaving the locking arms p and p' free. When the lever F' is moved to the reverse indicating or No. 3 position, as shown in Fig. 4, the locking arm p drops 45 into the recess or groove between the lugs p^2 , gravity effecting this movement. When the magnet P is energized it will lift its armature P' , and thereby swing the locking arm p on its axis at 10, so as to disengage the locking arm from the lugs p^2 , and will cause the locking arm p' to strike the bottom surface of the lug p^3 on the lever F' . The position of the parts is illustrated in Fig. 4^a, and permits of the lever F' being 60 moved to the fourth or reverse position, as shown in Figs. 5 and 5^a. As the lever moves to the position shown in Fig. 5, the locking arm p' rides off of the lug p^3 and drops down behind the same, its movement being effected by the armature P' under the in-

fluence of the attraction of the magnet P . This position of the parts is shown in Fig. 5, and at the same time the lever F is being moved to the full reverse position, the indication is being received and the mechanical interlocking released. The movement of the lever F' also breaks the circuit at the indicating spring contacts O' , as heretofore explained, and thereby deenergizes the magnet P , allowing its armature P' to drop back to its normal position, and this in turn allows the locking arm p' to drop away from its engagement with the lug p^3 , all as shown in Fig. 5^a. With the lever thus released it is free to be returned to the No. 2 or normal indicating position, which is shown in Fig. 1 of the drawings. Should there occur a cross or short circuit on the indicating wire while the lever is in the reverse position, as heretofore explained, the magnet P will be energized, thereby raising the armature P' and causing the locking arm p' to engage lug p^3 , thereby locking the lever against being returned to the normal indicating position, where there is a cross or short circuit on the indicating circuit.

The locking magnet M , indicated in Fig. 1, is shown in Figs. 3 to 5^a as located below the lever F' . It is conveniently a solenoid or hollow magnet through which the locking pin or part M^2 works upwardly into position to engage between lugs Z on the locking lever F' . When the lever F' is moved to the reverse indicating position No. 3, (Fig. 4), the space between the lug Z is directly over the rod M^2 on the armature of the magnet M , and as the current or power which operates the switch and signal, as heretofore explained, passes through the coils of the magnet M , the magnet is energized, thereby lifting the armature of the magnet M and locking the lever F' so that it cannot be moved to the No. 4 position while current is passing through the magnet and the switch or signal motor E . As soon, however, as the switch or signal is moved to the reverse position the circuit is broken at the motor, as heretofore explained, thereby deenergizing the magnet M and allowing its armature to drop back by gravity, so as to again release the lever F' and permit it to be moved to the fourth position, provided that a proper indication has been received through the indicating coils P .

Batteries R , R are the indicator batteries one being connected with contacts O of all levers and the other with contacts O' of all levers. The opposite sides of the batteries are connected with indicator returns R' , R^2 common to all stations from which indications are given. The common indicator returns have branches r' , r^2 at each station from which indications are given, adapted to be alternately connected with the individual station lines by contacts r^3 , r^4 on the

motor operated switch I. At the extension station C' the contacts r^3 , r^4 establish the indicator circuit from r' , r^2 through the branches N, N' to the individual line C' of station C, the indication in this instance being directly from the extension station through contacts in series therewith at station C after station C has operated and one indication is a true record of what has happened at both stations.

With the parts in the positions indicated in Fig. 1, both indicators show that the switches or signals are in normal position and by a movement of any lever to reverse indicating position the battery or generator G² will be thrown into circuit, causing that switch or signal to be reversed. The lever being released so as to be able to be moved to the reverse position will indicate that the switch or signal has reversed. Various arrangements of the indicating means and indicator operating circuits become practicable in combination with the two returns common to all stations and two sources of energy, such as batteries or generators. Thus, it is entirely practical to employ intermittent or alternating currents without lines in addition to the operating lines or the operating generators may themselves be utilized for generating indicating power and in Fig. 2 one arrangement for accomplishing this end is illustrated. In this arrangement shown in Fig. 2, the generators are both operating and indicating generators, each generator being the operating generator when a lever is moved in one direction and the indicating generator when a lever is moved in the opposite direction, one generator thus operating the motor while the other indicates and their functions are reversed according to the direction in which the lever is moved, *i. e.*, to reverse or set the switch or signal to normal.

The tower and stations are indicated generally as in Fig. 1 by the letters A, B, C and C', the levers by F and F' and the returns common to all stations by G, G'. The two generators are illustrated by batteries S, S' and instead of the single individual line from the tower to each station, two lines T, T' extend from the tower to each station, these lines T, T' alternately forming part of the operating and indicating circuits. Battery S is connected on one side with return G and on the opposite side with lever contacts s and s' , contact s moving into contact with lines T when the levers are moved in one direction and contact s' moving into contact with indicator contacts s^2 when the levers are moved in the other direction. Battery S' is connected on one side with return G' and on the opposite side with lever contacts s^3 , s^4 , contacts s^3 being moved into connection with lines T' when the lever is moved to break the T-line at s .

Contacts s^4 engage indicator circuit contacts s^5 when the levers are moved in one direction, while the indicator circuit contacts s' and s^2 are moved into engagement when the levers are moved in the opposite direction. 70 These indicator circuit contacts preferably move past each other and are insulated, as shown, on one face so as to complete the circuits only when the lever is moved in the proper direction and a continuation of the 75 movement in the same direction breaks the circuit. For instance, movement of a lever from position No. 1 to position No. 3 brings contacts s^4 and s^5 into engagement and a continuation of the movement to position No. 80 4 breaks the circuit and during the movement the contacts s' , s^2 have moved past each other without establishing the indicator circuit controlled by them.

Each indicator circuit from the battery S' and controlled by the contacts s^4 , s^5 includes one of the coils of an indicator magnet T² (conveniently a double wound magnet) and extends from said magnet to a contact t carried by the tower lever (F or F'). Contact t engages a contact t' on station line T when the lever is toward reverse position. Each indicator circuit from battery S and controlled by the contacts s' , s^2 also includes one of the coils of indicator magnet T² and 95 a lever operated contact t^2 adapted to engage a terminal contact t^3 of station line T' when the lever is moved toward home. At each station the motor U is preferably a double wound motor or provided with separate circuits or connections whereby it may be driven through one circuit to move the signal or switch in one direction and through the other circuit to move the signal or switch in the other direction. The 100 station lines T, T' are branched at each station, one branch of line T' being controlled by contact u on the motor operated switch U' and leading to one of the motor circuits, thence to the return G'. The other branch 110 is controlled by contact u' on the motor operated switch U' and leads directly to the other return G. One branch of line T is controlled by contact u^2 on the motor operated switch U' and leads through the other motor circuit to the return G while the other branch is controlled by contact u^3 on the motor operated switch U' and leads to the return G'. The switch U' is operated 115 by the motor as heretofore described in connection with the switch I and the arrangement is such that the motor leaves the switch with the contacts properly established for moving the switch in the opposite direction from that in which it was last moved. The extension station C' is equipped in a similar manner, the only difference being that the contacts at station C are arranged to extend their line connections to station C' and stations C' and C in 120 125 130

series control the indicator circuits, as will be readily understood from the description in connection with Fig. 1.

- In connection with the illustration in Fig. 2, the safety appliances and lock devices for the levers have been omitted in order to avoid confusion, except for the cut-out magnets K and K'. These cut-out magnets for each battery are shown as included in circuits extending to lever contacts V and V', the contacts V for the magnet K controlling the battery S are mounted on the levers in position to engage the contacts t' of lines T when the levers are moved upwardly, and the contacts V' of the magnet K' controlling the battery S' are located in position to engage the terminal contacts t^2 of the lines T' when the levers are moved downwardly, the arrangement in both instances being such that should a cross or short-circuit occur the magnets K or K' would be energized and the operating current from the battery or generator interrupted at the circuit breaker controlled by the magnet.
- As illustrated in Fig. 2, the parts are in what are termed normal indicating position; that is to say, the signals or switches are in normal position and the connections are established for indicating that such is the case; for instance, the battery S is now the indicating battery and the indicating circuit may be traced from said battery S through the contacts s' , s^2 , indicating magnet T², lever contact t' , line T', motor operated switch contact u' and common return G back to battery. With the parts in this position the battery S' has operated as the operating battery to move the motors and motor operated switches U' into the position in which they are illustrated; that is to say, current from battery S' passing through lever contact s^3 , line T', motor operated switch contact u , motor and common return G' has operated the motor to move the switch to normal position, break the circuit at u and establish a circuit at u^2 for operating the motor to move the signal or switch to reverse position. When it is desired to move the signal or switch to reverse position the tower lever is moved downwardly or toward the operator bringing contacts s into engagement with the terminal contacts of line T and current may now flow from the generator S through contacts s , line T, motor operated switch contact u^2 , motor, and common return G, back to generator S. When the lever is moved in this direction indicator contacts s' , s^2 are disengaged and indicator contacts S⁴, S⁵ are back into engagement, thus establishing an indicator circuit from the battery or generator S' and indicator current will flow from battery S' through indicator contacts S⁴, S⁵, indicator magnet T², lever contact t , line T, motor operated switch contact u^3

and common return G' back to the generator. With this arrangement the generators S, S' are alternately operating and indicating generators and each serves to perform its function independently of the other.

Having thus described my invention, what I claim as new and desire to secure by Letters Patent of the United States, is:—

1. A switch and signal operating system embodying an operator's station, a plurality of switch or signal stations, each having electrically controlled motor mechanism, an individual line extending from the operator's station to the motor mechanism of each switch or signal station, two returns both common to the motor mechanisms of all the stations, means at each switch or signal station controlled by the motor mechanism at that station for connecting the individual line for that station with the common returns alternately, means at the operator's station for connecting any individual line with either return, and means for supplying current to the lines.

2. A switch and signal operating system embodying an operator's station, a plurality of switch or signal stations, an individual line extending from the operator's station to each switch or signal station, two returns both common to a plurality of switch or signal stations, electrically controlled means at each switch or signal station for connecting the individual line with the returns alternately, independent means at the operator's station for connecting any individual line with either return, and means for supplying current through the lines to the electrically controlled means at each station.

3. A switch and signal operating system embodying an operator's station, a plurality of switch or signal stations, an operating motor at each station, an individual line extending from the operator's station to each switch or signal station, two returns both common to all stations, means operated by the motor at each station for connecting the individual line with the returns alternately, means at the operator's station for connecting any individual line with either return, and means for supplying current to the lines.

4. A switch and signal operating system embodying an operator's station, a plurality of switch or signal stations, an operating motor at each station, individual station lines one from the operator's station to each of the switch and signal stations, a plurality of returns common to all stations, means at each station operated by the motor for connecting the individual station line with the common returns in succession, manually controlled means at the operator's station for connecting any individual switch or signal station line with either return, and means for supplying energy to the lines.

5. A switch and signal operating system embodying an operator's station, a plurality of switch or signal stations, remote from the operator's station, two independent sources 5 of electrical energy, two operating circuits between the sources of energy and stations, an automatic electrically actuated switch at each signal or switch station controlled through both operating circuits and operating to automatically establish the circuits alternately, and manually controlled switches at the operator's station whereby the circuit including either source of energy may be established. 10
6. A switch and signal operating system embodying an operator's station, a distant switch or signal station, an operating motor at the distant station, a plurality of generators, line connections between the generators 20 and stations, a motor, a switch at the distant station operated thereby for establishing circuit connections between the motor and generators alternately, and a manually controlled switch at the operator's station also controlling the circuit connections between the generators and the motor at the distant station. 25
7. A switch and signal operating system embodying stations distant from each other, two independent generators, independent return lines between stations for the generators, a line between stations common to both generators, switches at both stations controlling the circuit connections between the 30 generators and line common to both generators and a motor mechanism receiving current from said generators through the lines and operating the circuit switch at the station where the motor mechanism is located. 35
8. A switch and signal operating system embodying an operator's station, a distant switch or signal station, two independent generators, an operating motor at the distant station, independent return lines including the respective generators, a line between the stations common to both generators, a motor operated switch at the distant station controlling the connections between 40 the independent returns and line common to both generators, a manually controlled switch at the operator's station controlling the connections between said independent generators and line common to both generators. 45
9. A switch and signal operating system embodying an operator's station, a plurality of distant switch or signal stations, two independent generators, independent returns, one for each generator each common to all the stations, individual lines each common to both generators and extending from the operator's station to each of the distant stations, motor mechanism at each distant station in the connection between the individual 50 line and common returns and a switch at each station operated by the motor mechanism controlling the connection between the individual line and common returns. 55
10. A switch and signal operating system embodying an operator's station, a plurality of distant switch or signal stations, two independent generators, independent returns one for each generator each return being common to all the stations, individual lines 60 extending from the operator's station to each distant station, each line being common to both generators, motor mechanism in the connection between the individual line and common returns, a switch governed thereby at each distant station controlling the connection between the individual line and common returns, and independent switches at the operator's station each controlling the connection between one individual line and the two generators, there being one switch at the operator's station for each distant station. 65
11. A switch and signal operating system embodying an operator's station, a plurality of distant switch or signal stations, two independent generators, independent returns one for each generator, each return being common to all the stations, individual lines 70 common to both generators extending from the operator's station to the distant stations, motor mechanism in the connection between the individual line and common returns, a switch governed thereby at each distant station movable to connect the individual lines with the common returns alternately, switches at the operator's station one for each distant station and each controlling the connection between an individual station line and the generators whereby at 75 both the operator's station and the distant station the individual lines may be placed in circuit with either of the common returns. 80
12. A switch and signal operating system embodying an operator's station, a plurality of distant switch or signal stations, independent generators, independent returns one for each generator each return being common to all the stations, individual lines common to all the generators extending from the operator's station to the distant stations, motor mechanism in the connection between the individual line and common returns, a switch at each distant station operated by 85 the motor mechanism and controlling the connection between the individual line and common returns and switches at the operator's station, one for each distant station controlling the connections between the individual line and common returns, whereby any generator may be included in circuit with the individual line of any station and one of the common returns. 90
13. A switch and signal operating system 95

embodying an operator's station, a plurality of distant switch or signal stations, independent returns common to all the stations, a generator included in each return, individual lines extending from the operator's station to each switch or signal station, motor mechanisms in the connections between the individual lines and common returns, automatic switches operated by the motor mechanisms at the last mentioned stations controlling the connections between the individual lines and common returns, manually controlled switches, one for each distant station located at the operator's station and each controlling the connection between an individual station line and all of the generators.

14. A switch and signal operating and indicating system embodying an operator's station, a distant switch or signal station, a motor located at the distant station, an indicator located at the operator's station, line connections between said stations, independent motor and indicator operating generators, a switch at the distant station controlled by the motor for establishing at that station both the operating and indicating circuits, and a manually controlled switch at the operator's station for establishing both the operating and indicating circuits.

15. A switch and signal operating and indicating system embodying an operator's station and a plurality of switch or signal stations, motors at the switch or signal stations, indicators one for each switch or signal station located at the operator's station, independent operating and indicating generators, independent returns common to all the stations there being a separate return through which current is supplied from each generator and a separate line common to the independent generators extending from the operator's station to each switch and signal station with a switch at each station for connecting the line and returns.

16. A switch and signal operating and indicating system embodying an operator's station, a plurality of switch or signal stations, a motor at each switch or signal station, indicators at the operator's station one for each switch or signal station, independent generators, independent returns common to all the stations and each including one generator, a line common to all generators extending from the operator's station to each switch or signal station, a motor operated switch at each switch or signal station controlling the connections between said individual lines and the common returns and a switch at the operator's station controlling a plurality of connections between the individual station line and the generators there being one switch at the operator's station for each switch or signal station.

17. A switch and signal operating and in-

dicating system embodying an operator's station, a plurality of distant switch or signal stations, an operating motor at each switch or signal station, an indicator at the operator's station for each switch or signal station, a return common to all the indicators and all the distant stations, an independent return common to all the operating motors of all distant stations, independent motor and indicator operating generators, individual lines extending from the operator's station to the distant stations, a motor operated switch at each station for connecting and disconnecting the individual station line with the returns and manually controlled switches at the operator's station for simultaneously connecting the operating and indicating generators with the individual lines to any station, said generators being included in the respective independent returns.

18. A switch and signal operating and indicating system embodying an operator's station, a plurality of distant switch or signal stations, an indicator for each distant station, an operating motor at each distant station, individual lines from the operator's station to the distant stations, a plurality of returns common to all stations and all operating motors, a plurality of returns common to all stations and all indicators, motor operated switches at the distant stations controlling the connections between the individual station lines and all returns, manually operated switches at the operator's station controlling the connections between individual station lines and all returns and independent generators included in the independent returns, said generators being common to all the distant stations.

19. A switch or signal operating system embodying switch or signal stations, an operating motor at each station, independent generators for operating said motors to move the signals or switches to normal and reverse positions, respectively, a switch in each generator circuit and a safety magnet controlling said switch having circuit connections with the generator connected for effecting the next succeeding movement of the switch motor.

20. A switch or signal operating system embodying switch or signal stations, an operating motor at each station, independent generators for operating the motors to move the signals or switches to normal and reverse positions, respectively, means for alternately connecting the generators in circuit with the motors, a magnetically operated switch controlling the operating circuit and circuit connections, whereby said switch is controlled by the generator included in the operating circuit for effecting the next succeeding movement of the motor.

21. A switch or signal operating system embodying switch or signal stations, an op-

erating motor at each station, independent generators for operating the motor to move the signals or switches to normal and reverse positions, respectively, motor controlled means for alternately connecting the generators in circuit with the motors, a magnetically operated switch controlling the operating circuit, said magnetically operating switch having circuit connections with the generator included in the operating circuit for effecting the next succeeding movement of the switch motor, whereby an accidental cross will interrupt the operating circuit.

22. In switch and signal operating systems embodying an operator's station and a plurality of switch or signal stations, an individual line extending from the operator's station to each switch or signal station, two returns both common to all the stations, means at each switch or signal station for connecting the individual line with the returns alternately, means at the operator's station for connecting any individual line with either return, means for supplying

current to the lines and magnetically operated switches for the returns included in branch circuits between the returns.

23. A switch and signal operating system embodying an operator's station, a plurality of switch or signal stations remote from the operator's station, two independent sources of electrical energy, line connections between the sources of energy and stations, an automatic switch at each signal or switch station whereby the sources of energy are alternately connected in the operating circuit, manually controlled switches at the operator's station whereby either source of energy may be connected in the operating circuit, automatic switches at the operator's station for breaking the circuits from the sources of energy, the switch for each circuit being included in a branch with the source of energy not included in the operating circuit.

PETER G. TEN EYCK.
